W. W. GARNER,
SUBMARINE DESTROYER,
APPLICATION FILED MAY 11, 1917.

1,247,659.

Patented Nov. 27, 1917.

UNITED STATES PATENT OFFICE.

WILLIAM W. GARNER, OF MISSION, TEXAS.

SUBMARINE-DESTROYER.

1,247,659.

Specification of Letters Patent.

Patented Nov. 27, 1917.

Application filed May 11, 1917. Serial No. 168,013.

To all whom it may concern:

Be it known that I, WILLIAM W. GARNER, a citizen of the United States, residing at Mission, in the county of Hidalgo and State 5 of Texas, have invented a new and useful Submarine-Destroyer, of which the following is a specification.

The device forming the subject matter 10 of this application is a projectile of the harpoon type, adapted to be dropped from an aeroplane, for the purpose of destroying a submarine or other vessel.

The invention aims to provide a structure 15 of the kind described which will pierce the water readily and maintain an upright position while moving downwardly from the aeroplane to the submarine or other vessel.

Another object of the invention is to provide novel means for supporting the stem 20 of the structure out of operative relation to the explosive, the construction being such that when the passage of the device is resisted to the necessary extent, the stem will impinge on the explosive and cause the 25 same to detonate.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

In the accompanying drawings,

Figure 1 shows in side elevation, a device constructed in accordance with the present invention;

Fig. 2 is a fragmental longitudinal section of the device, on an enlarged scale, parts appearing in elevation; and

Fig. 3 is a cross section taken approximately on the line 3—3 of Fig. 2.

In carrying out the present invention 50 there is provided a body 1 of approximately conical form, including a bottom 2 and a top 3, the bottom 2 having an entering point 4. In the bottom portion 2 of the structure there is formed a chamber 5 communicating 55 with an enlarged recess 6 in the bottom 2 to define a shoulder 7. The top 3 has a

flange 8 threaded as shown at 9 on the upper end of the bottom 2. The top 3 has a recess 10 communicating with a reduced bore 11 extended through the upper end of the 60 top 3.

A cartridge 12 is placed in the chamber 5 and includes a removable head 12^a having rim 14 supported on the shoulder 7. A ring 15 is placed in the recess 6 and bears on the rib 14 of the cartridge 12. Supported on the ring 15 and on the upper end of the bottom 1 is a frangible diaphragm 16. The invention comprises a stem 17 mounted slidably in the bore 11 and having an enlarged 70 head 18 received in the recess 10, the head being supplied with a firing projection 19. The head 18 is supported on the frangible diaphragm 16 when the top 3 is threaded onto the bottom 1 as shown at 9.

When the structure is dropped from an aeroplane, the head 1 enters the water readily, the point 4 facilitating the entry of the body. The frangible diaphragm 16 is strong enough so that it will not break 80 when the structure strikes the water. When, however, the point 4 strikes a relatively unyielding object, such as a submarine, then the diaphragm 16 will break, the stem 17 moving inwardly and the firing projection 85 19 will strike a cap 20 mounted in the butt of the cartridge 12, the material 21 in the cartridge being exploded, with obvious results.

The head 18 on the stem 17 permits the 90 entire device to be manipulated and handled by means of the stem, without causing the stem to pull out of the top 3. The ring 15 serves to prevent the cartridge 12 from moving upwardly, accidentally, and striking the 95 firing pin 19, thereby producing a premature explosion. The diaphragm 16 exercises a double function in that, in addition to serving as a means for supporting the stem, it constitutes a packing washer between the 100 bottom 2 and the top 3, preventing the entrance of water into the device.

Having thus described the invention, what is claimed is:—

A projectile of the harpoon type comprising a body having a chamber and an enlarged recess defining a shoulder; a cartridge in the chamber; a head for the cartridge including a rim overlying the shoulder; a top threaded upon the body; a 110 frangible diaphragm bound between the top and the upper end of the body; a ring fit-

ting in the recess and engaging the diaphragm and the head to hold the cartridge in the chamber, the ring being removable independently of the head whereby one ring 5 may be substituted for another to compensate for variations in the thickness of the rim, and the head being removable from the cartridge independently of the ring whereby one head may be substituted for another 10 to compensate for variations in the width of the ring; a stem slidable in the top and supported by the diaphragm, the stem and the top being provided with interengaging elements preventing a withdrawal of the 15 stem, the stem constituting a means for throwing the projectile, and projecting beyond the rear end of the top a sufficient

distance to give an appreciable added increment of weight to the stem whereby the stem will be advanced to form a firing 20 means for the cartridge when the forward end of the body strikes an obstacle, the projecting portion of the stem being of greater length than the combined lengths of the body and the top, and being of a common diameter 25 throughout.

In testimony that I claim the foregoing as my own, I have hereto affixed my signature in the presence of two witnesses.

WILLIAM W. GARNER.
